UNITED STATES PATENT OFFICE.

GEORGE R. BAILEY, OF BROOKLYN, NEW YORK, ASSIGNOR TO STERLING CASKET HARDWARE COMPANY, OF BROOKLYN, NEW YORK, A CORPORATION OF NEW YORK.

DESIGN FOR A CASKET-HANDLE LUG.

52,379.

Specification for Design. Patented Sept. 10, 1918.

Application filed May 31, 1918. Serial No. 237,660. Term of patent 7 years.

To all whom it may concern:

Be it known that I, GEORGE R. BAILEY, a citizen of the United States, residing at No. 502 Bedford avenue, in the borough of Brooklyn, county of Kings, and State of New York, have invented a new, original, and ornamental Design for a Casket-Handle Lug, of which the following is a specification, reference being had to the accompanying drawing, forming part thereof.

The figure is a plan view of a casket handle lug showing my new design.

I claim:

The ornamental design for a casket handle lug, as shown.

GEORGE R. BAILEY.

Witnesses:

A. M. VIKBERG,
VICTOR C. CORMIER.
